UNITED STATES PATENT OFFICE.

JAMES ROYAL FRUSHOUR, OF ANDREWS, INDIANA.

AUTOMOBILE HEATER.

Application filed June 10, 1926. Serial No. 115,081.

This application is a continuation in part of my U. S. application Serial No. 87,623, filed Feb. 11th, 1926.

The invention relates to improvements in automobile heaters of the type which heat air by contact with the exhaust pipe and direct it through a register in the floor boards of the machine.

The primary object of the invention is to provide a heater of the general type set forth, which is of extreme simplicity, may be quickly and easily installed without the use of screws, bolts, rivets or the like, may be removed with equal speed and ease, yet will be highly efficient and desirable.

Ordinarily, a casing portion of the device receives air, subjects it to the hot exhaust pipe and directs such air upwardly through a register, but it is a further aim of the invention to make unique provision for permitting direct passage of air through the above named casing portion instead of allowing such air to be trapped therein, when the register is closed.

Another aim is to make provision whereby the exhaust manifold and pipe leading therefrom are utilized for air heating.

With the foregoing in view, the invention resides in the novel subject matter herein-after described and claimed, the description being supplemented by the accompanying drawings.

Figure 1 is an elevation partly in section, showing the application of the invention.

Figure 2 is a top plan view of a register constructed in accordance with my invention.

Figure 3 is a vertical longitudinal section on line 3-3 of Fig. 2 showing the heater in condition for operation.

Figure 4 is a duplicate of Fig. 3 with the exception that it illustrates the relation of parts when the use of the heater is not desired.

Figure 5 is a rear end view.

Figure 6 is a vertical transverse section on line 6-6 of Fig. 3.

Figure 7 is a view similar to Fig. 6 but illustrating the manner in which the register and the air receiver may be either assembled or separated.

In the drawings above briefly described, B designates a portion of the floor boards of an automobile and P indicates a part of the usual exhaust pipe, beneath said floor boards, said pipe leading from the exhaust

manifold M. The boards B are formed with an opening O above the pipe P, said opening receiving the upper portion of an air receiver 7. In the preferred form of construction, this air receiver is formed from a single sheet metal plate bent upon itself centrally between its ends to provide it with a bottom 8 to contact with the lower side of the pipe P, and with a pair of side walls 65 9, the upper edges of the latter having projecting means such as the flanges 10, to lie upon the floor boards B. Due to the formation of the receiver 7 from sheet metal it possesses a degree of resiliency sufficient to 70 permit inward movement of the side walls 9 toward each other, so as to permit upward passage of the flanges or the like 10 through the opening O. Then, when the side walls are released, they move outwardly so that 75 the aforesaid flanges overlie the floor boards, holding the air receiver against downward movement, contact of the bottom 8 with the pipe P then serving to hold said receiver against any upward shifting. 80

Means are provided to prevent unintentional inward movement of the side walls 9 and in the present disclosure, said means consists of the wall 11 of a register 12, said wall fitting snugly between the upper portions of the side walls 9 and having appropriate spring arms 13 which curve outwardly and pass through openings 14 formed in the side walls 9. The arms 13 prevent accidental upward movement of the 90 register 12 from the air receiver 7, yet will permit such movement when force is applied, allowing the heater to be quickly and easily removed from the machine. 95

In the present showing, the register 12 embodies slots 15 through which air may escape from the receiver 7, the front end of the latter being in communication with an air-collecting jacket J around the manifold M, so that the air entering the receiver 7, will be heated before discharge through the slots 15. A sliding damper plate 16 is shown to control the slots 15. When this damper is open, the rear end of the air receiver 7 is closed by the means 100 described below, causing the trapping and heating of air in said receiver. When this damper 16 is closed, as shown in Fig. 4, the rear end of the receiver 7 is opened so that air may pass directly therethrough from 105 front to rear. 110

For closing or opening the rear end of the

receiver 7, in the manner set forth above, I prefer to use a door 17 which is hinged at 18 to the rear portion of the register wall 11, so that it may swing to the vertical closed 5 position of Fig. 3 or may swing outwardly to the open position of Fig. 4. A link 19 or some other adequate connection, is provided between the damper 16 and the door 17 and it will be seen by a comparison of Figs. 3 and 10 4, that when said damper is open, the door 17 is closed. Similarly, as soon as the damper 16 is moved to closed position, the link 19 automatically opens the door 17 as shown in Fig. 4. Thus, air may pass uninterruptedly 15 through the receiver 7 without being trapped and heated therein.

Excellent results may be obtained from the general construction herein disclosed but it is to be understood that the invention is 20 not restricted to the precise details selected for illustration herein. Various changes may be made within the scope of the invention as claimed.

In order to apply the device it is simply 25 necessary to form an opening in the floor boards. Then, the receiver 7 is passed upwardly astride the pipe P, its side walls 9 are sprung inwardly to permit passage of the flanges 10 through the opening O, and 30 the register 12 is inserted into the upper portion of the air receiver until the holding means 13—14 become engaged. Jacket J is now applied and the device is then in readiness for use. Whenever the heater is 35 to be removed from the machine, for instance when it is desired to elevate the floor boards, the register 12 may be, by the application of sufficient force to release the holding means 13—14, raised out of engagement 40 with the air receiver 7. Then, the side walls of the latter may be forced inwardly toward each other permitting the flanges or the like 10 to pass downwardly through the opening O, whereupon said air receiver may be readily removed. The device is exceptionally 45 simple and inexpensive and particular attention is directed to the fact that it may be quickly and easily applied and effectively secured in place without the use of any

fasteners such as screws bolts or rivets. Not 50 only is this advantageous when installing the device, but when removing or replacing it for one reason or another.

I claim:

1. An automobile heater comprising an air 55 receiver whose upper portion is adapted for reception in a floor board opening, said receiver having a bottom to contact with the lower side of an exhaust pipe, side walls rising from said bottom to straddle the pipe, 60 and projecting means on said side walls to lie upon the floor board, said side walls being inwardly movable to permit upward passage of said projecting means through the floor board opening when the heater is being 65 installed, and means for holding said side walls against unintentional inward movement after installation of the heater.

2. A structure as specified in claim 1; said bottom and side walls being bent from a single metal sheet; said projecting means consisting of flanges bent outwardly from the upper edges of said side walls.

3. An automobile heater comprising an air 75 receiver whose upper portion is adapted for reception in a floor board opening, said receiver having a bottom to contact with the lower side of an exhaust pipe, side walls rising from said bottom to straddle the pipe, and projecting means on said side walls to 80 lie upon the floor board, said side walls being inwardly movable to permit upward passage of said projecting means through the floor board opening when the heater is being installed, and a register for insertion within 85 the upper portion of the air collector and adapted to contact with said side walls to hold the latter against accidental inward movement after the heater is installed.

4. A structure as specified in claim 3; said 90 register and said side walls having inter-engaged means to normally hold the register against upward movement from the air receiver.

In testimony whereof I have hereunto 95 affixed my signature.

JAMES ROYAL FRUSHOUR.
